UNITED STATES PATENT OFFICE.

BERNARD LOEWE, OF ZURICH, SWITZERLAND.

SPINNING AND PIECING APPARATUS.

Application filed May 13, 1924. Serial No. 713,068.

To all whom it may concern:

Be it known that I, BERNARD LOEWE, a citizen of Turkey, residing at Zurich, in the Canton of Zurich, Republic of Switzerland, have invented certain new and useful Improvements in Spinning and Piecing Apparatus, of which the following is a specification.

This invention relates to spinning machines with a plurality of spinning devices comprising each a spinning tube formed with spinning eyes, and one or more discs rotatable around the axis of said tube.

According to this invention on this disc and eccentrically to the axis of said spinning eyes, one or more filament guides are provided by which the spun filament is polished and evened, and if desired, also receives a twist. Further the improved apparatus also allows of doubling one or more filaments to form a thread. According to the position of the nature of the filament guide the filament may be twisted or not and polished more or less thoroughly.

Two constructional forms of the improved apparatus of this invention are illustrated by way of example in the accompanying drawing in which:

Figures 1 and 2 are respectively a vertical section and a plan (from below) of a filament piecing device with a filament guiding eye adjustably mounted with varying eccentricity on the revolving disc.

Figure 3 is a section through a filament piecing device having two revolving discs of which the upper one contains a filament guide.

The spinning and piecing apparatus illustrated in Figures 1 and 2 consists essentially of a tube 1 with a piecing disc 2 situated beneath it formed with marginal notches 3. This tube and disc are rotatable in a casing 4 provided at the top with a screw-in tubular cover 5 which carries a fixed tube 6 (piecing tube) extending into the spinning tube 1. The usual fixed eyes 7 and 8 made of agate, glass or other suitable material are mounted on the cover 5 or spinning tube 6.

The actuation of the tube 1 with piecing disc 2 is effected by means of an endless driving belt 9 which is pressed against a disc 10, mounted on the tube 1, by means of a disc 11.

Below the notched disc 2 there is mounted as a filament guide, an eye 13 carried by

an arm 14 pivoted at 15. By shifting the arm 14, the eye 13 can be moved below the notch 16, nearer to or away from the center of the disc 2. The angle made by the silk filament 17 in passing from the eyelet 13 to the eye 7 can therefore be adjusted as desired. In its passage through the eye 7 the filament is rubbed so that it is polished and all its irregularities are evened. For the purpose of facilitating the threading of the filament through the eye 13, the latter may be brought to the center of the disc. By making this eye 13 sufficiently narrow so that it is capable of taking up the filament during the rotational motion of the disc 2, a certain amount of twist can be given to the filament. By providing two eccentric eyes 13 below the disc 2, two silk filaments can be twisted together.

The apparatus illustrated in Figure 3 comprises two revolving discs 20 and 21. The lower disc 21 is notched in a similar manner as the disc 2 of the first example and serves for the piecing of the filaments (silk filaments of cocoons for instance). The upper disc 20 carries an eccentric filament guide 18' in the form of a ring or traveller adapted to be brought in different positions with regard to the axis of the spinning eyes. In this spinning and piecing device the cocoon filaments pieced by the disc 21 are twisted by the disc 20 as they pass out of the eye 8', thus promoting the adhering together of the separate cocoon filaments which are to be united to form one compound filament. A further result is a better polishing action in consequence of the inclined position of the filament between the eye 8' and the filament guide 18' and also in consequence of the twist given to the filament. This twist is lost again on the spools of the winding apparatus, but however it has helped in uniting and polishing the filaments. The funnel-shaped cavity formed by the disc 20 may be utilized for containing solutions of an adhesive or the like, for treating the filament in its passage between the eye 7' and 8' or between the eye 8' and the filament guide 18'. The spinning tube 6' is held within the piecing tube 1 for instance by means of screws 25.

When the improved apparatus is to be used also for doubling the filaments issuing from the tube 6, two conical discs are employed, one on each end of said tube and

each provided with an eccentric thread guide and a driving disc.

What I claim is:

1. In a spinning machine, spinning devices comprising each a spinning tube provided with spinning eyes, at least one disc capable of rotating about the axis of said tube, a filament guide mounted on said disc in an eccentric manner relatively to the axis 10 of said spinning eyes so as to polish and even the filaments during their passing through said guide and the next spinning eye.

2. In a spinning machine, spinning devices each of which have a spinning tube provided with a spinning eye on each end, a disc capable of rotating about the axis of said tube, a filament guide mounted on said disc in such a manner that the amount of

its eccentricity in relation to the fixed spinning eyes can be varied.

3. In a spinning machine, spinning and piecing devices comprising each a tube provided with a fixed spinning eye on each piecing end, a disc loosely mounted on this tube and adapted to rotate about it, the cavity of the disc containing a solution of an adhesive through which the filament is moved, a filament guide mounted on said disc in an eccentric manner relatively to 30 the spinning eyes of the piecing tube.

In testimony whereof I have affixed my signature in presence of two witnesses.

BERNARD LOEWE
